(57) **CLAIM**

The ornamental design for a feed pusher blade apparatus, as shown and described.

DESCRIPTION

FIG. 1 is a front elevational view of the feed pusher blade apparatus, with the blade member being positioned in a straight forward orientation, showing my new design; FIG. 2 is a rear elevational view thereof;

FIG. 3 is a left side elevational view thereof depicting blade member positioned in the straight forward orientation;

FIG. 4 is a right side elevational view thereof;

FIG. 5 is a top plan view of the feed pusher blade apparatus with the blade member being positioned in the straight forward orientation;

FIG. 6 is a bottom plan view thereof;

FIG. 7 is a right, front perspective view of the feed pusher blade apparatus with the blade member being positioned in the straight forward orientation;

FIG. 8 is a right, front perspective view of the feed pusher blade apparatus with the blade member being positioned in the angled right operative orientation; and,

FIG. 9 is a right, front perspective view of the feed pusher blade apparatus with the blade member being positioned in the angled left operative orientation.
